US00D912725S

(12) **United States Design Patent** (10) Patent No.: **US D912,725 S**
(45) Date of Patent: **** Mar. 9, 2021**

(54) **POS MACHINE**

(71) Applicant: **PAX COMPUTER TECHNOLOGY (SHENZHEN) CO., LTD.**, Guangdong (CN)

(72) Inventors: **Shaowen Luo**, Guangdong (CN); **Xiaoping Lei**, Guangdong (CN); **Guohua Huang**, Guangdong (CN)

(73) Assignee: **PAX COMPUTER TECHNOLOGY (SHENZHEN) CO., LTD.**, Guangdon (CN)

(**) Term: **15 Years**

(21) Appl. No.: **29/641,306**

(22) Filed: **Mar. 21, 2018**

(30) **Foreign Application Priority Data**

Jan. 9, 2018 (CN) 201830009261.9

CLAIM

The ornamental design for a POS machine, as shown and described.

DESCRIPTION

FIG. 1 is a first perspective view of a POS machine showing the new design;

FIG. 2 is a second perspective view of the POS machine;

FIG. 3 is a front view of the POS machine;

FIG. 4 is a rear view of the POS machine;

FIG. 5 is a left view of the POS machine;

FIG. 6 is a right view of the POS machine;

FIG. 7 is a top view of the POS machine; and,

FIG. 8 is a bottom view of the POS machine.

The broken lines in the drawings depict portions of the POS machine that forms no part of the claimed design.

1 Claim, 8 Drawing Sheets
